GAS PRODUCTION

Application filed November 23, 1923. Serial No. 676,473.

This invention relates to a new and improved method and apparatus for gas production and enrichment and more particularly to a method and apparatus particularly adapted for the enrichment of blast furnace gases by means of the reduction of the carbon dioxide to carbon monoxide and also by the addition to the gas of water gas or coal gas or both.

10 Blast furnace gases, although produced at high temperatures and in large quantities in the operation of blast furnaces, are not satisfactorily adapted for many metallurgical purposes due to their relatively low calorific

15 value. While specific reference is made to blast furnace gas, the process is adapted for use with other like gases having a carbon dioxide content which may be reduced to carbon monoxide. Such gases are the products of combustion from lime kilns, ore reducing furnaces, heating furnaces used in metallurgical work and other similar furnaces.

It is an object of the present invention to provide a new and improved method and apparatus adapted for the enrichment of blast furnace gases or the like. It is a further object to provide a method and means of this character adapted to enrich the blast furnace gas not only by breaking down the CO_2 to CO but also by enriching the gas with coal gas, water gas, oil, tar, or any combination of such enriching mediums.

It is also an object to provide an apparatus and method adapted for this purpose by the use of bituminous coal as the enriching agent, the coal being prevented from massing together by means of stirring mechanism and being prevented from clinkering by a two zone method of operation.

It is an additional object to provide an apparatus adapted to be operated to enrich the gas by complete gasification of the fuel or by partial gasification and the production of coke if so desired.

It is a further object to provide an apparatus adapted for such gas enrichment which apparatus is also adapted for the independent production of either producer gas or water gas or both.

Other and further objects will appear as the description proceeds.

I have illustrated certain preferred embodiments of my invention in the accompanying drawings, in which:

Figure 1 is an elevation, partly in section, showing one form of apparatus adapted for carrying out my method;

Figure 2 is a plan view of the form of apparatus shown in Figure 1;

Figure 3 is a horizontal section taken on line 3—3 of Figure 1;

Figure 4 is a fragmentary elevation showing a modified form of construction;

Figure 5 is a vertical section through a modified form of apparatus;

Figure 6 is a plan view of the form of construction shown in Figure 5;

Figure 7 is a horizontal section taken on line 7—7 of Figure 5; and

Figure 8 is a fragmentary section taken on line 8—8 of Figure 7.

Referring first to the form of construction shown in Figures 1 to 3, the blast furnace or other gas intake passage 11 divides into the two passages 12 and 13 controlled by valves 14 and 15, respectively. These two passages lead to the stacks 16 and 17 of the regenerators 18 and 19. The stacks 16 and 17 are controlled by valves 20 and 21. The regenerators 18 and 19 are provided at their lower ends with the passages 22 and 23 which join to form passage 24 which leads to the vertical uptake 25. This uptake 25 discharges under the mushroom head 26 into the bottom of the gas unit 27. The mushroom head 26 is hollow and is connected to pipe 28 through which air, steam or water may be introduced. The passages 48 and 49, controlled by valves 50 and 51, enter the Y-passage 22 adjacent the regenerator 18. The passage 48 is adapted for the introduction of air and the passage 49 for the introduction of steam. The similar passages 52 and 53, controlled by valves 54 and 55, enter the opposite Y-passage 23.

The pan 29 constitutes the bottom of the unit 27 and is provided with the ash discharge passage 30 controlled by valve 31. The rotating member 32, as best shown in

Figure 3, is provided with the circular rack 33 driven by pinion 34, this pinion being driven by any suitable source of power. The member 32 is provided with the vanes 35 which serve to thrust the ash outwardly towards the periphery of the ash pan 29. The lower portion of this pan is preferably filled with water as indicated at 36, this water serving to cool the bottom.

- 10 The lower side walls 37 of the unit are preferably formed of cast metal staves having pipes 38 cast therein, these pipes being adapted to carry circulating cooling water. This portion of the wall 37 is provided with 15 the lower outwardly sloping portion 39 which is joined to the upper cylindrical portion 40 by the horizontal portion 41.

The tuyères 42 extend through the cylindrical wall 40 and are connected at their 20 outer ends to the bustle pipe 43. The bustle pipe 43 has connected thereto the passages 44 and 45, controlled by valves 46 and 47, respectively. These passages are adapted to supply air and steam to the bustle pipe 25 respectively.

The upper portion of the gas unit 27 is shown as having a fire-brick wall 56 surrounded by a metal shell 57. The upper end of the unit is provided with the fuel intake 30 passage 58 and carries the mechanism 59 adapted to rotate the stirrer 60 whereby the fuel bed may be agitated. The passage 61 leads from the upper end of the gas unit to the waste heat boiler 62 and economizer 63. 35 The gases are carried from the economizer 63 through the passage 64 to any gas using or gas holding apparatus.

Figure 4 shows a modified construction of the lower side walls of the gas unit. In this 40 form of construction these walls 65 are formed of brick work and are cooled by the water-cooled plates 66 which are similar to the bosh plates now in common use in blast furnaces.

45 Referring now to the form of construction shown in Figures 5 to 8, the gas unit 68 is located above the regenerator 69. As best shown in Figure 6, the gas intake passage 70 is divided and enters the right end of the 50 regenerator through passage 71 and the left end of the regenerator through passage 72. The passage 70 is controlled by valve 73, passage 71 by valve 74 and passage 72 by valve 75. The discharge stack 76 leads upwardly from passage 71 and is provided with valve 77. A similar stack 78 provided with valve 79 leads upwardly from the passage 72 adjacent the left end of the regenerator.

The regenerator is provided with the central wall 80 having therein the two series of 60 passages 81 and 82. The passages 81 which open to the left are fed from the air header 83, controlled by valve 84, and the passages 82 are fed from air header 85, controlled by 65 valve 86. The passage 87 connects the regen-

erator and the gas unit and discharges under the mushroom head 88. This mushroom head 88 is hollow and is connected with passages 89 through which air, steam or water may be introduced.

This gas unit 68 is similar in general construction to that shown in Figure 1 and is provided with the tuyères 90 connected to the bustle pipe 91. The bustle pipe 91 has connected thereto the two passages 104 and 105, controlled by valves 106 and 107, these passages being adapted to introduce air and steam into the bustle pipe respectively. The gas unit is also provided with the stirrer 92 and with the fuel intake opening 93. The gas discharge passage 94 leads to the upper end of the fixing chamber and carbureter 95. The oil pipe 96, controlled by valve 97, also enters the upper end of this fixing chamber. The lower end of the fixing chamber is connected by passage 98 with the waste heat boiler 99. The upper end of the waste heat boiler 99 is connected by passage 100 with the wash box 101. From the wash box the gas discharge passage 102, controlled by valve 90 103, leads to any suitable gas using or gas holding apparatus.

In the operation of the form of apparatus shown in Figures 1 to 4, the gas to be enriched is led from the blast furnace or other source through passage 11 and thence through passage 12, valve 14 being open, to the stack 16 of the regenerator 18 and down through the regenerator. During this period, the passage 13 is closed off by means of valve 15. 95 From the regenerator 18, the heated gas passes through passage 22 to passage 24 and thence through uptake 25 and discharges under the mushroom head 26 into the lower end of the gas unit 27.

At the same time, a portion of the gas passes from passage 22 into passage 23 where it meets a stream of air introduced through passage 52 with which it burns. The combined stream passes up through the regenerator 19 and the products of combustion pass out the stack. The amount of gas entering this regenerator is controlled by means of the stack draft. It will be understood that the processes going on in the two regenerators will be periodically reversed when the regenerator giving up its heat to the gases is cooled down and the regenerator being heated has reached the desired temperature. When reversing the operation, steam may be introduced through passage 49 to clear the regenerator 18 of gas before the mixed air and gas are burned therein. The regenerator 19 is similarly blown out by steam introduced through passage 53.

The gas introduced into the gas unit under the mushroom head is at a relatively high temperature due to the fact that it may be led from the blast furnace, lime kiln, ore reducing furnace or other furnace producing

gas high in CO_2 while hot and its temperature is also increased in the regenerator. As the gas is introduced under the mushroom head, air, steam, or water, or any combination thereof, is introduced through 28 into the head, the air serving to cool the head and also to burn with the gas and the fuel in the lower part of the unit. This combustion serves to remove, as far as possible, the residual carbon in the bottom part of the generator and to leave an ash substantially free from objectionable clinkers. The ash zone is at a temperature below the melting point of the ash as in water gas practice and the gas leaves the zone at a similar temperature. The temperature in this lower zone will vary from approximately twenty-two hundred degrees Fahrenheit adjacent the combustion zone if the temperature of that zone is held that high down to approximately the temperature of the incoming gases adjacent the mushroom head.

The gas with its CO_2 content partly reduced to CO then rises through the fuel into the zone between and above the tuyères 42 which is the zone of maximum heat and combustion. The temperature in this zone may be approximately twenty-two hundred degrees Fahrenheit, although it is not necessary that such a high temperature be maintained. The tuyères are used for the introduction of steam or air or steam and air alternately, the air serving by combustion to raise the temperature of the fuel, which at the time it reaches this point has been reduced to coke, and the steam serving to generate water gas by its action upon the incandescent coke.

As the gas to be enriched passes through this zone, it is at a high temperature and the fuel is also at a high temperature so that the desired reduction of the CO_2 to CO is completed. As the heated gas, now enriched by the reduction of its CO_2 , and also, when steam is used, by the addition of water gas, rises through the coal in the upper part of the generator, thereby carbonizing and distilling the coal therein. The raw coal in the upper portion of the generator is thus reduced to coke by the action of the heated gases and the gas is enriched by the coal gas. An important feature of this method of operation lies in the fact that the coal gas and volatiles from the coal are not carried through the hottest zones with the resultant cracking and lowering of B. t. u. value per cubic foot.

The stirrer in the top of the gas unit is an important feature, particularly when bituminous coal is used as a fuel as it prevents the caking of the fuel bed and keeps it open for the free passage of the gases. The gases thus pass substantially uniformly through the mass and thus reduces it uniformly to coke.

From the gas unit the enriched gases pass out to the waste heat boiler 62 and economizer 63 which serve to recover a large portion of

the sensible heat of the gases. The gas is then led through passage 64 to any desired gas holding or using apparatus.

The water-cooled metal stave construction of the lower part of the gas unit shown in Figure 1 serves to preserve the lines of the unit. Also the water-cooled construction prevents the adhesion of side wall clinkers, and the angle at the lower edge of the cylindrical portion 40 causes the material to tend to drop from this edge rather than to mass on the sides and follow down as side wall clinkers.

The alternative construction shown in Figure 4 is shown as having substantially the same interior lines. In this construction the wall is formed of fire brick and the lines are preserved by the insertion of water-cooled bosh plates, the offset in the side wall having the same effect as above described in connection with the other form.

The form of installation shown in Figures 5 to 8 is operated in a manner similar to that just described. The gas containing carbon dioxide which is to be enriched is led from the gas source through passage 70 to passage 71 and thence into the regenerator 69. Valves 73, 74 and 79 are open and valves 77 and 75 are closed. The air valve 84 is open and valve 85 closed.

The gases pass upward through the checkerwork in the right-hand half of the regenerator wherein they are heated. The major portion of the gas passes through uptake 87 and into the gas unit 68 under the mushroom head 88.

A portion of the gas passes over the top of the wall 80 where it meets air introduced through the plurality of passages 81. The air and gas burn as they pass down through the checkers in the left half of the regenerator and then pass out through passage 72 and out through stack 78. The amount of this flow is controlled by means of the control of the draft in the stack.

The operation of the gas unit in the form of installation is exactly similar to that of the gas unit in the installation shown in Figures 1 to 4 and previously described. The enriched gases pass through passage 94 to the top of the carburetter 95. Here they may be further enriched by the introduction of oil through pipe 96, valve 97 being opened.

From the bottom of the carburetter 95 the gases pass through the waste heat boiler 99 where they give up some of their heat and from the boiler they go to the wash box 101. From the wash box the gases are led off through passage 102, valve 103 being opened, to any suitable gas using or holding apparatus.

It will be understood that the regenerator 69 will be reversed in use. When the right hand checkerwork has been cooled down and the left-hand checkerwork sufficiently heated

the valves 74, 79 and 84 will be closed and valves 75, 77 and 86 opened. The gas is then heated in the left half of the regenerator and a portion is burned with air from the air header 85 to heat the right-hand side of the checkerwork.

It will be observed that the present method of operation of the gas units results in complete control both of the enrichment of the 10 gas and the gasification of the fuel in the unit. The amount of air introduced under the mushroom head may be varied and also the proportions of air or steam through the tuyères. Thus the temperatures in both zones 15 of the unit are under control. Also the amount of water gas generated may be controlled by the proportioning of the steam admitted.

An important feature of the two-zone 20 method of operation lies in the fact that the lower zone may be maintained at a temperature which will not be sufficiently high to cause the agglomeration of the ash particles into objectionable clinker, this temperature 25 varying with the fusing point of the ash of the particular fuel used.

If desired, the unit may be operated without reducing the fuel to ash and coke may be withdrawn at the lower end of the unit.

30 The unit is also adapted for use independently as a gas producer or as a gas generator. If operated to produce water gas, air and steam will be introduced intermittently in alternation as is customary in water gas 35 practice. The steam would be admitted through the tuyères and the air through both or either the tuyères and mushroom head as desired. If used as a gas producer, both steam and air mixed may be introduced through 40 both the mushroom head and the tuyères or either.

In any of the above described methods of 45 operation, steam may be introduced through the regenerators. In this method, steam may or not also be introduced through the tuyères.

The process in the gas unit may be intermittent and a part or all of the blast gas formed by blowing air into the unit through the bustle pipe may be passed downwardly 50 through the regenerator. This method would be especially valuable where the unit is used as an independent gas generator or producer.

It will be obvious to those skilled in the art to which the invention relates that modifications may be made in details of procedure 55 without departing from the spirit of the invention which is not limited as to those matters or otherwise than as the prior art and the appended claims may require.

60 I claim:

1. The process of raising the calorific value of a hot gas containing a considerable proportion of carbon dioxide, which consists; in superheating the gas by passing through a 65 regenerator, then passing the hot gas through

a zone of coke and ash at a high temperature, next through a zone of coke at a higher temperature, and then through a zone of bituminous coal, the passage of the gas serving to distill and to coke the coal in said last zone and thereby enrich the heating gas with the distillation products, and agitating the last-named fuel zone during the passage of the gas.

2. The process of raising the calorific value 75 of a gas containing a considerable portion of carbon dioxide, which consists; in passing the gas through a zone of partly consumed coke at a high temperature, next through a zone of coke at a higher temperature, introducing air and steam alternately directly in said latter zone, and then passing the gas through a zone of substantially raw bituminous coal and thereby distilling and coking the coal and enriching the mixed gases with 80 the products of distillation, and agitating said coal during the passage of the gas.

Signed at Philadelphia, Pennsylvania, this 19th day of November, 1923.

CHARLES W. ANDREWS. 85
